[57] **CLAIM**

The ornamental design for an adjustable fluorescent lamp, as shown and described.

DESCRIPTION

FIG. 1 is a top, front, right hand side perspective view of an adjustable fluorescent lamp showing my new design;

FIG. 2 is a left side perspective view thereof, the telescoping arm being retracted and the clamp and light turned to an alternate position;

FIG. 3 is a bottom perspective view thereof, the arm being straightened and the clamp being turned to an alternate position;

FIG. 4 is a top plan view of the lamp as shown in FIG. 1;

FIG. 5 is a left side elevational view of the lamp as shown in FIG. 1; and

FIG. 6 is a front elevational view of the lamp as shown in FIG. 1.

FIG.1

FIG.2

FIG. 4

FIG. 6
